Primary Examiner — Charles D Hanson

(57) **CLAIM**

The ornamental design for a heart valve cover, as shown and described.

DESCRIPTION

FIG. 1 is a first, side perspective view of a first portion of a heart valve cover;

FIG. 2 is a first side view thereof;

FIG. 3 is a second side view thereof;

FIG. 4 is a third side view thereof;

FIG. 5 is a fourth side view thereof;

FIG. 6 is a top side view thereof; and,

FIG. 7 is a bottom side view thereof.

Broken lines are also for illustrative purposes only and form no part of the claimed design.

1 Claim, 7 Drawing Sheets# US D926,322 S
